CLAIM

The ornamental design for an electric scooter, as shown and described.

DESCRIPTION

FIG. 1 is a front, right and bottom perspective view of electric scooter, showing my new design; FIG. 2 is a rear, left and top perspective view thereof; FIG. 3 is a front view thereof; FIG. 4 is a rear view thereof; FIG. 5 is a top plan view thereof; FIG. 6 is a bottom plan view thereof; FIG. 7 is a left side view thereof; FIG. 8 is a right side view thereof; FIG. 9 is an enlarged view of portion of FIG. 1 thereof; FIG. 10 is an enlarged view of portion of FIG. 1 thereof; and, FIG. 11 is an enlarged view of portion of FIG. 2 thereof. The evenly broken lines disclose unclaimed portions of the electric scooter; the dash-dot type broken lines disclose unclaimed boundaries of the isolated views; the broken lines form no part of the claimed design.
